UNITED STATES PATENT OFFICE

HENRY HAEGLER, OF GENEVA, SWITZERLAND

AIR CLEANER

Application filed May 7, 1925, Serial No. 28,579, and in France January 28, 1925.

The present invention relates broadly to filters or air cleaners, and more particularly to cleaners of a construction adapting them for use with an internal combustion engine, 5 although the utility of the invention is not limited in this respect.

In my co-pending application, Serial No. 8,407, filed February 11, 1925, I have disclosed and claimed advantages of a construction, for the general purpose herein contemplated, having a filtering medium preferably maintained under tension and subjected both to vibrations and jars. The present invention discloses one form of cleaner embodying 15 these features of construction and adapted for use with carburetors supplying internal combustion engines.

In the accompanying drawings there are shown, for purposes of illustration only, certain preferred embodiments of the present invention, it being understood that the drawings do not define the limits of my invention, as changes in the construction and operation disclosed therein may be made without departing 25 either from the spirit of the invention or the scope of my broader claims.

In the drawings:

Figure 1 is a vertical sectional view through one form of cleaner constructed in accordance with the present invention;

Figure 2 is a detail sectional view on an enlarged scale, through one of the cleaning members;

Figure 3 is a detail sectional view, on still a larger scale, illustrating one manner of clamping the filtering medium in position;

Figure 4 is a top plan view of a filtering member constructed in accordance with the disclosure of Figure 3;

Figure 5 is a top plan view of one form of separating and striking member;

Figure 6 is a view corresponding to Figure 4 and illustrating a slightly modified embodiment of the present invention;

Figure 7 is an enlarged detail sectional view on the line VII—VII of Figure 6;

Figure 8 is a side elevational view showing one commercial application of an air cleaner constructed in accordance with the present invention; and

Figure 9 is a view similar to Figure 8, but partly broken away, illustrating still another application of the present invention.

In carrying out the present invention, in order to obtain all of the desired advantages, it is desirable to utilize a filtering medium of suitable material, such as bolting cloth, free from fuzz, and thereby providing free interstitial flow areas. It is also desirable that this filtering medium be mounted in such manner that it is maintained in a state of tension, and also free to vibrate, so that the filtering surfaces thereof are maintained free from obstruction.

In carrying out the present invention, there may be provided a suitable support, preferably in the form of a tube 2, having a large portion of its surface provided with a series of openings 3, these openings preferably being arranged in juxtaposed rows. The tubular support 2 is adapted to receive a plurality of filtering members 4, each filtering member being preferably so constructed as to cooperate with one row of the openings 3, the members preferably being slipped onto the support in juxtaposed relationship.

After all of the filtering members are in position on the tubular support, they are adapted to be clamped in position thereon. Conveniently, this may be accomplished by providing a cup-shaped member 5, secured in any manner to the tubular support, preferably at some distance from the end thereof to provide a projecting portion for the purpose hereinafter pointed out. The member 5 forms a stop and enclosure for the filtering members 4. The opposite end of the support 2 may be closed by a disk 6, having a central boss 7. This boss may be threaded to receive

a clamping bolt 8, passing through a second cup-shaped member 9, and provided with a flange 10, adapted to cooperate with the filtering members and compress the same as the clamping bolt is screwed into position. The member 9 is preferably of considerably

smaller diameter than the member 5, and may be centered in position therein by means of spring fingers 11.

Each of the filtering members may comprise annular strips of bolting cloth or other

material 12, preferably arranged in pairs, and clamped at their outer edges by a U-shaped metallic clamping ring 13. The inner edges may be similarly clamped in separate fastening pieces 14. The pieces 14 may be held in predetermined spaced relationship by means of shouldered rivets 15 cooperating therewith to thereby dispose each pair of strips 12 in inwardly diverging relationship. 5 The desired tension may be maintained on the strips 12 by means of split expanding rings 16 located between the strips and bearing outwardly against the binding pieces 13. If desired, the binding pieces may be further 10 crimped to assist in holding the strips in position by forming them with a series of depressions 17.

During assembly, the filtering members before described, are adapted to alternate with separating and striking rings 18, preferably 20 comprising a central annular portion adapted to cooperate with the tubular support and having radiating arms 19. Alternate arms may be formed with projections 20 extending 25 in opposite directions. The length of the arms 19 is preferably such that the projections 20 will be directly opposite the edge binding pieces 13 when the parts are in assembled position, thereby tending to strike 30 the same when the cleaner is subjected to vibration and free the filtering surfaces of any dust particles. During assembly, a tight joint is preferably formed between each of the filtering members and each surface of the 35 separating and striking members by interposing a felt washer 21 therebetween. It will be understood that these washers are compressed and thereby hold the parts firmly in position and prevent any air leakage between 40 the filtering members.

In Figures 6 and 7 there is illustrated a slightly modified embodiment of the present invention, in which both the edge binding pieces 13' and the inner binding pieces 14' are formed with clamping depressions 17'. The inner binding pieces 14' are also illustrated as being provided with radially extending spring arms 21^a, tending to maintain the strips 12' of the filtering medium in 50 spaced relation, and also serving to maintain the desired tension thereon. The outer edges of the strips may be maintained in spaced relation by a yieldable or plastic washer 21'.

In Figure 8 of the drawings I have illustrated one method of utilizing an air cleaner constructed in accordance with the present invention. In accordance with this embodiment, the projecting portion of the support 2, before referred to, may be clamped in 55 operative relation to the air intake of the carburetor 22 by means of a clamping ring 23. In operation, the air is drawn between the cup-shaped members 5 and 9, and thereafter comes into contact with the filtering members. Due to the depression existing within 60

the tubular support 2, the air is drawn through the filtering members into the interior of the tubular support, and thence passes to the carburetor. The vibrations of the motor which is supplied by the carburetor to 70 which the present air cleaner is adapted to be attached, as well as road vibrations of the vehicle, tend to maintain the surfaces of the filtering members in a continuous state of vibration, thereby maintaining the same free 75 from adhering particles of dirt and the like. Also, by maintaining the filtering medium in a state of tension, and by providing free interstitial flow areas, an effective passage of the air is insured. 80

In Figure 9 of the drawings there is illustrated another method of commercially utilizing the present invention. In accordance with this disclosure, the air cleaners may have an open end portion engaged within 85 a suitable casting 24, carried by the dash 25 of a vehicle. The casting 24 may be formed with a projection 26 adapted to cooperate with a flexible conductor 27 or the like, delivering to the intake of the carburetor. It will 90 be understood that the operation of this form of the invention corresponds with that already described.

With a construction of the character disclosed herein, it is possible to provide a plurality of similar filtering members adapted to be easily assembled in position, to thereby provide a large filtering surface offering a minimum resistance to the air being cleaned. This constitutes one of the advantages of the 100 present invention, as in this manner the dimensions of the cleaner may be reduced to a minimum while maintaining a large filtering area.

Further advantages of the present invention arise from the provision of a perforated support carrying a plurality of filtering members. Still other advantages of the invention arise from the construction of the filtering members whereby the filtering medium is effectively maintained in a state of tension free to vibrate, whereby its dust separating capacity is increased, it being an established fact that a fast moving filtering medium separates more dust than a fixed one. 105

I claim:

1. A filter, comprising a support, a plurality of adjacent separately removable annular filtering members mounted thereon, and striking members clamped between adjacent filtering members and cooperating with at least some of said filtering members, substantially as described. 110

2. A filter, comprising a support, a plurality of separately removable filtering members mounted on said support, and separating and striking members alternating with said filtering members and clamped therebetween, substantially as described. 115

3. In an air cleaner, a body, a filtering

member formed of discontinuous annular screen-like elements comprising cloth and assembled to provide an annular filtering surface, means supported by the cloth of certain of the elements for tensioning the cloth therein, the outer peripheries of said elements being free to oscillate by inertia, an axial support for said member, and stop means against which said elements are adapted to strike upon oscillation thereof, substantially as described.

4. In a filter comprising a unitary support, a plurality of adjacent separately removable annular filtering members mounted thereon, and a plurality of striking members secured to the support intermediate the filtering members and extending outwardly from the support into position for striking some of said filtering members.

5. In an air cleaner, a filtering member formed of discontinuous annular screen-like elements, each comprising cloth and assembled to provide an annular filtering surface having sides which converge toward the outer periphery thereof, a stop member means for tensioning the cloth in each element for supporting its outer periphery, and an axial support for the inner peripheries of said filtering elements whereby said elements are mounted to permit relative oscillation therebetween by inertia and to engage with said stop member.

6. A filter, comprising a support having a plurality of circumferentially extending rows of openings formed therein, a separate filtering member cooperating with each row of openings, and striking means carried by the support with the free edges extending outwardly therefrom and terminating within the peripheries of said filtering members and each cooperating with one of said filtering members, substantially as described.

7. In an air cleaner, a support adapted to be mounted on a vehicle normally having continuous and irregular movement, the support having a plurality of openings therein, filter strips secured to the support between certain of the rows of openings, certain of the filter strips being secured at their outer edges for constituting filtering members, tensioning means provided within each filtering member, and striking members secured to the support within the edges of said filtering members, and extending outwardly into juxtaposition to the edges of the filtering members, whereby inertia causes the filtering members and the striking members to collide during movement of the air cleaner, substantially as described.

8. In an air cleaner, a support adapted to be mounted on a vehicle normally having continuous and irregular movement, the support having a row of openings therein, an annular filter member surrounding the row of openings comprising a pair of converging

filtering strips secured together at their outer edge, tensioning means for the filtering strips and a striking member secured to the support adjacent the end of a diverging strip of the annular filter member with its outer end disposed adjacent to the outer edge of the filtering member, whereby upon movement of the air cleaner the filtering member is caused to collide with the striking member and have vibratory motion imparted thereto, substantially as described.

9. A filter, comprising a tubular support, a plurality of filtering members slipped on said support, and spaced overlapping cup-shaped covers extending around said members, substantially as described.

10. A filter, comprising a tubular perforated support, a plurality of individually removable annular filtering members slipped on said support and surrounding the perforation therein, means for maintaining said filtering members under tension, and spaced overlapping cup-shaped covers for said members, substantially as described.

11. In an air cleaner, a filtering member formed of separate annular screen-like elements assembled to provide an annular filtering surface, separate tensioning means carried by certain of said elements, the outer peripheries of said elements being free to oscillate by inertia, and an axial support for said member, substantially as described.

12. In an air cleaner, a filtering member formed of a plurality of annular screen-like elements comprising cloth and assembled to provide an annular filtering surface, the outer peripheries of said elements being free to oscillate by inertia, means for tensioning the cloth of each element to support its outer periphery, and a perforated axial support for said member, substantially as described.

In testimony whereof I have hereunto set my hand.

HENRY HAEGLER.
